US00D864216S

(12) **United States Design Patent** (10) Patent No.: **US D864,216 S**
 Theodore et al. (45) Date of Patent: **** Oct. 22, 2019**

(54) **DISPLAY SCREEN WITH GRAPHICAL USER INTERFACE**

(71) Applicant: **Adobe Inc.**, San Jose, CA (US)

(72) Inventors: **Brian Theodore**, Los Altos, CA (US);
James Dibble, Kensington, CA (US);
Elisha J. Fitch-Cook, East Lansing, MI (US)

(73) Assignee: **Adobe Inc.**, San Jose, CA (US)

(**) Term: **15 Years**

(21) Appl. No.: **29/615,318**

(22) Filed: **Aug. 28, 2017**

Related U.S. Application Data

(63) Continuation of application No. 29/560,199, filed on Apr. 4, 2016, now abandoned.

(57)

CLAIM

The ornamental design for a display screen with graphical user interface, as shown and described.

DESCRIPTION

The sole FIGURE is a front view of a display screen with graphical user interface.

The outermost broken line perimeter illustrates a display screen and forms no part of the claimed design. The remaining broken lines illustrate portions of a graphical user interface and form no part of the claimed design.

1 Claim, 1 Drawing Sheet
